UNITED STATES PATENT OFFICE.

JOHN T. TOWSLEY, OF CINCINNATI, OHIO.

WHEEL FOR TRUCKS.

SPECIFICATION forming part of Letters Patent No. 746,900, dated December 15, 1903.

Application filed September 6, 1902. Serial No. 122,292. (No model.)

To all whom it may concern:

Be it known that I, JOHN T. TOWSLEY, a citizen of the United States of America, and a resident of Cincinnati, county of Hamilton, 5 State of Ohio, have invented certain new and useful Improvements in Wheels for Trucks, of which the following is a specification.

My invention relates to the journal-forks of wheels for trucks. I have found that these 10 forks in use break at the point where the shank of the fork contacts the lower end of the bracket which is secured to the truck-body. I have found, likewise, that a solid wrought-metal shank breaks more quickly 15 than a hollow metal shank which has been interiorly annealed, but still these hollow annealed shanks likewise break at the point aforementioned.

The object of my invention is to provide a 20 fork for truck-wheels which will be strong at the point upon which the greatest strain is brought and in which the strain is more evenly distributed. This object I attain by the means described in the specification and illustrated in the accompanying drawings, in 25 which—

Figure 1 is a view showing one end of the truck-body, with the bracket shown in longitudinal section and the fork embodying my 30 invention shown in elevation. Fig. 2 is a longitudinal sectional detail view of the shank of fork embodying my invention upon an enlarged scale. Fig. 3 is a transverse vertical sectional view of the same. Fig. 4 is a horizontal sectional view of the same, taken upon line $z z$ of Fig. 2.

Referring to the parts, brackets A are attached to the front and rear ends of the truck-body a in the usual manner. In the top and 40 bottom of each bracket A are vertically-alined holes a' and a'' , the top one, a' , being of smaller diameter than the lower and its under side being beveled. Shank b of journal-fork B has at its upper end a reduced portion and at the 45 lower end of the reduced portion a beveled portion B' . At the lower end of the shank is an enlarged collar B^2 . Bracket A rests upon shank b , with the beveled portion B' contacting the beveled edge of hole A' and the lower 50 end of the bracket standing free above collar B^2 . The weight of the truck being thus

borne by the upper end of the shank, some strain is taken off of the portion of it coming near the lower end of bracket A.

When the truck is being moved, either 55 pushed or drawn, the wheels occupy a position parallel to the direction in which the truck is moved, the swiveled joint allowing the wheel to occupy this position. The strain, therefore, upon the shank occurs along its 60 vertical longitudinal diameter—that is, the diameter which lies midway between the forks.

The shank embodying my invention is made hollow of cast metal, has two vertical ribs b^2 65 b^3 formed upon the interior of the shank at diametrically opposite points and upon the aforesaid vertical longitudinal diameter of the shank. The ribs extend from a point in the shank below the lower edge of bracket A 70 up into the interior of the shank well above said point. The interior of shank b and the ribs b^2 b^3 are annealed. By thus placing ribs upon the interior of the shank at its longitudinal vertical axis I not only secure a greater 75 thickness of metal at that point, but I likewise secure a much larger annealing-surface, so that I find shanks made in this manner will stand a much greater strain than shanks as heretofore made.

80 What I claim is—

1. A journal-fork for trucks whose shank consists of a hollow metal casting having upon its interior a vertical rib upon its vertical longitudinal diameter and being interiorly annealed substantially as shown and described.

85 2. A journal-fork for trucks whose shank consists of a metal tube having upon its longitudinal diameter two internal ribs at diametrically opposite points and being interiorly 90 annealed substantially as shown and described.

3. In combination with a truck a bracket having an upper and a lower vertically-alined hole the upper one being smaller in diameter 95 than the lower, a journal-fork whose upper end has a shoulder upon which the edges of the upper hole of the bracket bear to support the weight of the truck substantially as shown and described.

100 4. A bracket having upper and lower vertically-alined holes, the upper one being re-

duced in diameter, in combination with a journal-fork having a hollow metal shank with ribs upon its interior upon its vertical longitudinal diameter, the interior of the shank being annealed, and near the upper edge of the shank an external collar upon which the edges of the upper hole in the

bracket rests to support the weight of the truck substantially as shown and described.

JOHN T. TOWSLEY.
